CLAIM

The ornamental design for a dental ceramic stain tray, as shown.

DESCRIPTION

FIG. 1 is a perspective view of the dental ceramic stain tray showing my new design;
 FIG. 2 is a top plan view thereof;
 FIG. 3 is a bottom plan view thereof;
 FIG. 4 is a front elevation thereof;
 FIG. 5 is a rear elevation thereof;
 FIG. 6 is a side elevation thereof; and
 FIG. 7 is a side elevation of the dental ceramic stain tray opposite to that shown in FIG. 6.
